United States Patent Office

Des. 180,179
Patented Apr. 30, 1957

180,179

DISPLAY RACK

Errol G. Elliott, Fort Worth, Tex., assignor to Williamson-Dickie Manufacturing Company, Fort Worth, Tex., a corporation of Texas

Application January 4, 1955, Serial No. 33,824

Term of patent 14 years

(Cl. D80—9)

Fig. 1 is a perspective view of a display rack showing my new design; and

Fig. 2 is a side view thereof.

I claim:

The ornamental design for a display rack, as shown.
